J. V. PERRIN,
TICKET HOLDER,
APPLICATION FILED SEPT. 7, 1920.

1,393,696.

Patented Oct. 11, 1921.

Inventor:
John V. Perrin,
by Arthur A. Randall
Atty

UNITED STATES PATENT OFFICE.

JOHN V. PERRIN, OF LYNN, MASSACHUSETTS.

TICKET-HOLDER.

1,393,696.

Specification of Letters Patent. Patented Oct. 11, 1921.

Application filed September 7, 1920. Serial No. 408,666.

To all whom it may concern:

Be it known that I, JOHN V. PERRIN, a citizen of the United States, residing at Lynn, in the county of Essex and State of Massachusetts, have invented certain new and useful Improvements in Ticket-Holders, of which the following is a specification.

My invention relates to ticket holders of that class which are applied to the backs of car seats and it has for its object to provide an improved ticket holder of this kind.

With this end in view my invention consists of a ticket holder for car seats made from a single piece of sheet material bent to conform to the shape of the seat and comprising a panel adapted to fit flatwise against the side of the seat having an integral laterally projecting flap at its top adapted to be fastened flatwise against the edge of the seat, the tickets, being slid into position under the panel and held by the latter in position against the seat back. A holder having this construction and mode of operation has the advantage that it presents no projections liable to become entangled with the clothing of the occupant or occupants of the seat and, moreover, the tickets are held flatwise against the side of the seat so that they cannot be broken or accidentally displaced. Other features of my invention are hereinafter pointed out.

In the accompanying drawings:

Figure 1 is a perspective view of the upper portion of a car seat equipped with my improved ticket holder.

Fig. 2 is a plan view of my improved ticket holder.

Fig. 3 is a front elevation of the ticket holder shown in Figs. 1 and 2.

Fig. 4 is a section on line 4—4 of Fig. 3, the seat back being indicated by dotted lines.

Fig. 5 shows a modification.

My improved holder, as shown in Figs. 1 to 4, inclusive, is made from a single piece of sheet metal bent to provide a panel 1 adapted to fit flatwise against the cushion side 2 of the back of car seat, said panel having at its top a pair of laterally projecting flaps 3 adapted to fit flatwise against the edge 50 of the seat back 2 and to occupy positions between the usual cleat 4 and the edge of back 2. The flaps 3 are formed with holes 5 through them to receive two of the screws 6 by which the cleat 4 is fastened in place. As 55 will be clear these two screws also fasten the holder securely in place.

The panel 1 is formed with a slot 7 therethrough which is somewhat greater in length than the width of the tickets the holder is to accommodate, and the material 60 of panel 1 at one side of the slot 7 is off-set relatively to the material of said panel at the opposite side of said slot. This off-set portion of the panel 1 is indicated at 8. Most car seats are covered with plush that is 65 supported by cushioning material incorporated within the seat back so that the latter is more or less yielding and a ticket may be readily entered in slot 7 and pushed down so that its lower end occupies a position between panel 1 and the plush. The off-set portion 8 holds the plush back so that it cannot close slot 7, protects the plush at the point of greatest wear and provides a smooth surface over which the end of the ticket 75 slides freely as it is being entered in slot 7. Also, the off-setting of the portion 8 provides a pocket within which the tickets are confined so that they cannot be displaced sidewise. In Fig. 4 a ticket in position 80 within the holder is indicated by dotted lines at T.

The holder may also be used by sliding the tickets under the lower portion of the panel 1 as indicated by dotted lines at T in 85 Fig. 1.

The holder shown in Fig. 5 is constructed as above described except that the holder of said Fig. 5 is made with a single flap 3^a formed with a single screw hole 5^a.

My invention provides a ticket holder of simple, inexpensive and efficient construction, which is particularly adapted for advertising purposes as shown in the drawings. The panel 1 is preferably made of a 95 size and shape to have an advertisement printed or embossed thereon and the position of the holder immediately in front of the passenger, or passengers, using it makes it practically impossible for the latter to fail 100 to see and read the advertisement.

What I claim is:

1. A ticket holding attachment of the character described consisting of a single piece of sheet metal bent to provide a panel 105 adapted to fit flatwise against the cushion side of the back of a car seat and an integral laterally projecting flap at the upper end of said panel adapted to be fastened flatwise against the edge of said back, said 110 panel being formed with a ticket receiving hole through which the ticket is shoved edge-

wise into position between the panel and the cushion side of the seat, so that it is yieldingly clamped against the inner side of the panel by said cushion.

5. 2. A ticket holder of the character described consisting of a single piece of sheet metal bent transversely to provide a panel adapted to fit flatwise against the side of the back of a car seat and to hold in position 10 against the latter a ticket inserted under said panel, and an integral laterally projecting flap at the upper end of said panel adapted to be fastened flatwise against the edge of said back, said panel being formed 15 with a ticket receiving slot, the portion of said panel at one side of said slot being inwardly off-set relatively to the portion of said panel at the opposite side of said slot to cause said inwardly off-set portion to hold 20 the material of the cushion side of the seat back away from said opposite side.
3. A ticket holding attachment of the character described consisting exclusively of a single piece of sheet metal bent to provide 25 a panel adapted to fit flatwise against the cushion side of the back of a car seat and an integral laterally projecting flap at the upper end of said panel adapted to be fastened flatwise against the edge of said back, 30 said panel being formed with a ticket receiving opening and having the portion of said panel immediately above said opening inwardly off-set relatively to the portion of the panel at the opposite side of said opening so as to provide a pocket for the upper 35 part of a ticket whose lower end portion has been shoved edgewise through said opening into position between the lower part of the panel and the cushion side of the seat.

4. The combination with the back of a car 40 seat provided at its edge with a cleat fastened to said back by screws or the like, of a ticket holder consisting of a single piece of sheet metal bent transversely to provide a panel adapted to fit flatwise against the 45 side of said seat back, and an integral laterally projecting flap at the upper end of said panel fitted flatwise against the edge of said back and disposed between said edge and said cleat, said flap being formed with 50 a hole through it for the reception of one of the cleat fastening screws by which the holder is secured in position on said back, and said panel being formed with a horizontal ticket receiving slot with the portion of 55 said panel above said slot inwardly off-set to hold the material of the seat away from the slot and to prevent the upper portion of a ticket from being bent outwardly when inserted edgewise in said slot. 60

5. A ticket holding attachment of the character described consisting of a single piece of sheet metal bent to provide a panel adapted to fit flatwise against the cushion side of the back of a car seat and an integral 65 laterally projecting flap at the upper end of said panel adapted to be fastened flatwise against the edge of said back, said panel being formed with a horizontal ticket receiving slot and having the portion thereof immediately above said slot inwardly off-set relatively to the material of the panel at the lower side of the said slot so as to provide 70 a pocket for the ticket having a shoulder at each side thereof for holding the ticket 75 against lateral displacement.

JOHN V. PERRIN.
